CLAIM

The ornamental design for a decanter with stopper, as shown and described.

DESCRIPTION

FIG. 1 is a front elevational view of a decanter with stopper, showing my new design, the rear elevational view being the same;

FIG. 2 is an end elevational view thereof, viewed from the right of FIG. 1, the opposite end elevation being the same;

FIG. 3 is a top plan view thereof; and

FIG. 4 is a bottom view thereof.
